APPARATUS FOR CHARGING OR FILLING
METAL CAPSULES

Carl F. Lozon, New York, N. Y.

Application December 7, 1934, Serial No. 756,551

17 Claims. (Cl. 226—73)

My invention relates to apparatus for charging or filling and sealing containers with a fluid under pressure, such for example as metallic capsules for use in carbonating water or beverages.

5 The principal general objects of the invention include the provision of apparatus for producing at a relatively rapid rate a succession of charged containers or capsules and wherein parts to be assembled are automatically fed to the 10 assembling mechanism which operates to compress the fluid or gas during the assembling operation.

In the embodiment of the invention herein disclosed, I have shown capsules of the type above mentioned composed of flanged body portions and caps united at the flanges by mechanism for successively bringing together the bodies and caps at a definite station where they are united by crimping the flange of one around the other while compressing the fluid or gas as above mentioned. 20 I have also shown separate feeding means for the bodies and caps, and an ejector for the assembled capsules, all of which are synchronized and operate in step with the assembling means.

25 All of the objects and advantages of the invention will become more apparent and will be pointed out during the course of the following detailed description of the accompanying drawings, in which

30 Fig. 1 is a perspective view of a press or machine with mechanism embodying my invention applied thereto;

Fig. 2 is an enlarged side elevation partly in section of mechanism embodying my invention;

35 Fig. 3 is a view taken on the line 3—3 of Figs. 2 and 7;

Fig. 4 is a view taken on the line 4—4 of Fig. 7;

Fig. 5 is an enlarged view taken on the line 5—5 of Fig. 3;

40 Fig. 6 is an enlarged view taken on the line 6—6 of Fig. 3;

Fig. 7 is a view taken on the line 7—7 of Fig. 3;

Fig. 8 is a view taken on the line 8—8 of Fig. 7;

45 Fig. 9 is a view taken on the line 9—9 of Fig. 7 and showing the assembling mechanism with a body and cap just prior to assembly;

Fig. 10 is a view similar to Fig. 9 showing the same parts during the assembling operation and at the stage when the fluid is being admitted for 50 compression; and

Fig. 11 is a view similar to Figs. 9 and 10 showing the parts in the final assembling stage.

In Fig. 1, the numeral 2 designates a standard or support of the press which is mounted on the base 3, and which is provided with brackets 4 just

above the base, and at its top with a journal for a shaft 5, driven by the wheel 6, which in turn may be driven by any suitable source of power. The forward ends of the brackets 4 are supported by rods 7, the lower ends of which receive nuts 8 5 beneath the brackets, and the upper ends of the rods are secured to extensions 9 on the top of the support 2.

The brackets 4 support a bed plate 10 on which parts of the apparatus embodying my invention 10 are mounted. A shaft 11 is secured to the bed plate, as shown in Fig. 7, by a nut 12 threaded on the reduced screw threaded end 13 of the shaft. Shaft 11 also has a flange 14 adjacent its lower end which rests on top of the bed 10. The upper 15 end of the shaft 11 is mounted through a sleeve 15, and as shown in Figs. 4 and 7, the sleeve 15 is provided with a pair of pins 16 which extend into grooves 17 on the shaft 11. At their lower ends the grooves are substantially straight and 20 at their upper ends are curved around the shaft for a purpose hereinafter explained. The sleeve 15 is mounted through a bushing 18, which is also mounted through a turret 19 and a head or top plate 20 which is attached to the usual cross head 25 or ram of the press. The upper end of the sleeve 15 is screw threaded and receives lock nuts 21.

The cross head or ram of the press and the head 20 are reciprocated by the usual connecting rod 21', the upper end of which is mounted 30 on an eccentric on the shaft 5, so that as the connecting rod 21' is reciprocated the head 20 and turret 19 are raised and lowered.

At one side of the bed 10 there is a bracket 25 which supports at its upper end, a tube 26 35 down which the capsule bodies B are fed from any suitable source of supply and by any suitable means. The lower end of the tube 26 is partially cut away providing an arcuate lip 27. A lever 28 is pivotally mounted at 29 on a part 40 30 carried by the tube 26. One end of the lever has a projection 31 extending across the end of the lip 27. At its other end the lever 28 has a beak 32 and another beak 33 intermediate its ends. The beaks 32 and 33 are spaced apart a 45 distance substantially equal to the length of the capsule body B, and the underside of the tube 26 is provided with a slot through which the beaks may project into the tube, as presently described. It will be noted that pivot 29 is 50 located intermediate the beaks 32 and 33, and a coil spring 34 is attached to the upper end of the lever 28, and also to a screw 35 to normally hold the lever in the position shown in Fig. 7 with the beak 33 engaging the lowermost capsule 55

body and supporting the column of bodies in the tube. Obviously, if the end 31 of the lever 28 is depressed below the lip, the lever is rocked on its pivot and the beak 32 is inserted in 5 through the slot to engage the next to the lowermost body and hold the column while the lowermost is discharged, due to the movement of the beak 33 opposite to the movement of the beak 32. The mechanism and means for effecting this 10 discharge of the bodies will be hereinafter described.

At the other side of the bed 10 adjacent the head 20, there is a chute designated generally by the numeral 36, which is shown more in detail in Fig. 8. The chute comprises side pieces 15 37 to the bottoms of which are secured angle strips 38 which receive the marginal portions of the caps C. As shown, the domes of the caps extend into the space between the angle strips 20 38. A guard plate 39 is mounted down the center of the chute above the space between the angle strips and may be supported by the cross pieces 40 which connect the sides 37. A bracket 25 41 may support the chute and be attached to any fixed support as shown in Fig. 7. At the lower end of the chute there is a lever 42 pivotally mounted at 43 on a part supported by the chute. The lever 42 has beaks 44, 45 similar to the beaks 32, 33 on the lever 28. The beak 45 is positioned at the end of the chute, and the beak 30 44 at a point above the end, the beaks being spaced apart a distance substantially equal to the diameter of the caps, so that the caps may be received between the beaks for the feeding 35 operation, as hereinafter explained.

A transfer slide for the caps is positioned beneath the end of the chute and comprises a plate 46 (see Figs. 2, 3 and 7) having a cap receiving portion 47 into which the caps fall when released from the chute. Plate 46 is slidably mounted between guides 48 and the plate is provided with an opening 49 having on opposite sides thereof stops 50. A lever 51 is pivotally mounted at 52 on the bracket 53 having a portion 40 extending into the opening 54 in the bed 10, and through which opening the lower end of the lever 51 projects. The upper end of the lever 51 is provided with a roller 55 disposed in the opening 49 between the stops 50. The upper face of plate 46 is provided with a cam surface 46' in which is disposed the end 43' of the lever 43. The mechanism for effecting and the manner of feeding the caps from the chute successively will be hereinafter described.

The turret 19 is provided with a plurality of 55 openings 60, there being four shown in Figs. 3 and 4, and which receive sockets or dies 61 containing a compressible packing 62 in its upper end with a coil spring 63 located in a reduced bore in the upper end and bearing against the compressible packing 62. The diameter of the openings in the sockets or dies is such as to frictionally receive the capsule bodies. The sockets are located at equidistant circumferentially spaced points on the turret and the means presently described for inserting the capsule bodies, assembling the caps and bodies, and for discharging the assembled capsules, are located at 60 points corresponding to the location of three of the sockets when the turret is at rest.

As previously mentioned, the head 20 is raised and lowered a predetermined distance at predetermined times by the connecting rod 21'. The rotation of the turret is accomplished by the 75 raising and lowering movement of the head

through the pin and slot connections 16, 17, shown in Figs. 4 and 7. The lower end of the sleeve 15 is formed as a ratchet, there being four teeth shown in Fig. 4 and designated by the numeral 65. A collar 66 surrounds the shaft 11 and carries a pawl 67 which is pivoted to the collar 66 at 68. The other end of the pawl is normally urged toward the ratchet teeth 65 by a coil spring 69 seated in a recess 70 in the turret. When the head 10 is raised it carries with it the 10 turret and the associated parts, and as the pins 16 engage in the curved parts of the grooves 17, the sleeve 15 begins to turn so that the ratchet tooth which is in engagement with the end of the pawl 67 rotates the collar 66 and turret a 15 quarter of a turn. As the head moves down and the pins move again through the curved portions of the grooves in reverse direction, the sleeve 15 is also turned in reverse direction and the ratchet teeth ride past the end of the pawl 67 20 without turning the turret. It is during the rotating movement of the turret that the parts to be assembled are relatively arranged, and during the downward movement brought into engagement compressing the fluid between them.

In Figs. 3 and 5, I have shown a brake which frictionally engages the turret, the brake comprising a plug 72 having a shank extending into an opening 73 in a depending part 74 of the head 20. The outer end of the opening 73 is 30 screw threaded to receive a nut 75 between which and the plug 72 is compressed a coil spring 76 normally urging the plug into frictional engagement with the turret 19. I also provide means for oppositely locking the turret against 35 rotative movement during the assembling and other operations, and the brake above described is for the purpose of cooperating with the locking mechanism shown in Figs. 2, 3 and 6. A fixed support 77 is secured to the frame of the machine 40 above the head and is provided with a bore 78 into which projects a pin 79. A shaft 80 is rotatably mounted through the head 20 and is provided with a groove 81 into which the pin 79 projects. The groove is curved to provide for 45 oscillating the shaft 80 as the head and turret are raised and lowered. A lever 82 is keyed to the lower end of the shaft 80 by a pin 83. The lever extends out beyond the edge of the turret and is provided with a pin 84 having a depending 50 portion 85 with a flattened surface. This flattened surface of the depending part 85 is disposed in an opening in one end of a pawl 86 confronting a cam formation 87 in said opening. The pawl is pivotally mounted on the depending 55 end of the stud 88 which is threaded into the head 20. The other end of the pawl has a beak 89 adapted to engage the notches 90 in the turret, the end of the pawl having the beak 89 being urged by coil spring 91 toward the turret. 60 The spring is mounted around a screw 92 extending through the side wall of the bed or head 20 and into the end of the pawl 86, the head being recessed at 93 to accommodate the spring. The notches 90 correspond to the number of 65 sockets which receive the capsule bodies and are so positioned that they are engaged successively by the beak 89 of the pawl 86 to hold the turret against rotative movement when the parts of the capsule are being fed, and assembled. 70 The mechanism for effecting the feeding of the parts of the capsules, assembling the same, and discharging the assembled capsules will now be described.

Referring especially to Figs. 1 and 3, the shaft 75

5 is shown provided with a beveled gear 95 meshing with a similar gear 96 on a shaft 97 which extends from adjacent the upper end of the frame 2 where it is journaled in a bearing 99 toward the lower end of the frame where it is journaled through a bearing provided by a bracket 100. The lower end of the shaft 97 is keyed to a beveled gear 101 in mesh with a similar gear 102 on the shaft 103 extending beneath the bed 10. As shown in Fig. 3, the shaft 103 is journaled through boss 104 on the bed 10 and a bracket 105 beneath the bed. The shaft also has keyed thereto a beveled gear 106 meshing with a beveled gear 107 on the shaft 108 also extending beneath the bed 10 at right angles to the shaft 103 and journaled through bracket 109. The opposite end of the shaft 108 is keyed to beveled gear 110 meshing with a similar gear 111 on the shaft 112 substantially parallel to the shaft 103 but at the opposite end of the bed plate and journaled through brackets 113.

Referring now to Fig. 7, the lever 114 is shown pivotally mounted on a fixed pivot 115 carried by a bracket 116 above the bed 10. The upper end of the lever 114 is formed as a post 117 of a diameter slightly less than the inner dimension of the capsule bodies. The lower end of the lever is provided with a cross pin 118 which is disposed in the forked end 119 of another lever 120 pivotally mounted at 121 on a pin supported by a bracket 122 beneath the bed 10. The lever 120 extends through an opening 123 in the bed and its lower end supports a roller 124 adjacent the cam 125 on the shaft 103. The cam is so constructed or formed that it oscillates the levers 120 and 114 in synchronism with the movements of the turret. In other words, when the turret is raised the lever 114 is swung to the dotted line position of Fig. 7 where the post 117 contacts the end 31 of the dog 28 releasing the lowermost capsule body which slides onto the post 117. The levers 120 and 114 are then swung to the full line position of Fig. 7 and assume such position just as the pins 16 in the shaft 11 enter the straight portion of the groove 17, so that as the turret lowers, the capsule body is inserted in the socket 61 which has been positioned directly above the post 117.

Still referring to Fig. 7, it will be noted that the shaft 112 carries a cam 126 and the cam is in alignment with the roller 127 on the lower end of the lever 51. The construction of the cam 126 and its movements are such as to oscillate the lever 51 and reciprocate plate 46, whereby the cam surface 46' oscillates lever 42 by moving end 43' to feed the caps to the assembling mechanism now to be described. The caps successively slide into recess 47, and as plate 46 moves over part 138 deposits the caps on top of member 128.

On top of the bed 10 on the side of the shaft 11 opposite the capsule body feeding mechanism and adjacent the cap feeding mechanism, there is mounted a post 128. The upper end of the post is formed of the same shape as the caps to receive the same. As clearly shown in Fig. 9, the dies or sockets which receive the capsule bodies have a concave portion or peripheral groove 129 in their lower face around the capsule body. Rods 130 are slidably mounted through the flange of the post 128, and through the bed 10 and are connected at their lower ends by a cross head 131. The head 131 has a boss 132 through which is mounted a rod 133, the upper end of the rod being screw threaded into the bed 10. A strong coil spring 134 has one end surrounding the boss 132

to bear on the cross head 131, and a flange nut 135 is screwed onto the lower end of the rod 133 to partially compress the spring 134 and to hold the spring in place around the rod. A lock nut 136 may also be provided to maintain the nut 135 in place. The upper ends of the rods 130 are connected into the flange 137 of the tubular member 138, which, in conjunction with the end of the post 128 forms part of the compression chamber for the gas. Therefore, to tightly seal this chamber a packing 139 is inserted between the post and the member 138 and is compressed by gland nut 140 which screws into the member 138. The top of the member 138 is provided with a channel which receives a gasket 141. When the turret is lowered, the end of the socket containing the capsule body abuts the gasket 141.

As shown in Figs. 9-11, a valve casing 142 is screw threaded into an opening in the wall of the member 138. The inner end of the casing 142 is provided with a port 143 normally closed by the valve head 144 on the stem 145 mounted through the casing and surrounded by packing 146 compressed by a gland nut 147 which is screw threaded into the outer end of the casing. Lock nuts 148 are threaded onto the outer end of the stem 145, and a coil spring 149 is compressed between the lock nuts 148 and the gland nut 147 normally pushing the stem outwardly to hold the head 144 against the port 143. The port 143 communicates with a passage 150 through the casing 142, and a tube or hose 151 leading from a source of gas supply is attached to the casing in communication with the passage 150. A bracket 152 is provided with a collar 153 which surrounds the part 138, and is attached thereto by screw 154 and key 154'. A lever 155 is connected at 156 to the bracket 152 and the upper end of the lever 155 is provided with an adjustable abutment 157 in alignment with the end of the stem 145. The lever 155 extends through an opening 158 in the bed and its lower end is relatively long and straight and provided with a block 159 for engagement by a cam 160, which, as shown in Figs. 2, 3 and 10-12, is keyed on the shaft 108.

The remaining part of the apparatus in accomplishing the fulfillment of the purposes of the invention is to effect discharge of the assembled capsules from the turret. Such apparatus is shown best in Figs. 2 and 3, wherein the head 20 is shown provided with a depending bracket 161 at its rear in which is journaled a pin 162, carrying a lever 163. A coil spring 164 is anchored at one end at 165 to the bracket and has its other end extending into the pin as at 166, so that the lever is normally held up against the turret. One end of the lever 163 is provided with a bumper 167 for engagement with a pad 168 on top of a bracket 169 supported on the bed 10. The other end of the lever 163 is provided with a slot 170 disposed in the path of the capsules as the turret rotates. Obviously, when the turret is elevated the end of the lever having the slot 170 is in engagement with the turret, and as the turret rotates the bead on the capsule is moved into the slot, so that when the turret descends the lever is tripped when the bumper 167 hits the pad 168, ejecting the capsule as shown in Fig. 2 into chute 171.

The operation of the apparatus is as follows: To start, a capsule body is inserted in the socket which is disposed at the front of the machine, and then when the shaft 5 is rotated, the head 20 is raised and lowered effecting rotation of the turret step by step in the manner previously

described. As the head descends on its first stroke the socket which was at the front of the machine is moved into alignment with the member 138. A cap was fed down onto post 128 when the parts were in the position of Fig. 9, by operation of lever 51 and plate 46. Therefore, as the turret descends the capsule body is brought down above the chamber provided by the part 138, as shown in Fig. 10, and at which time the valve 144 is opened to permit gas to flow into the chamber and capsule body. When a predetermined amount of gas has flowed into the chamber, which of course is determined by the length of time the valve head is opened by the cam 160, the valve is closed, and further descending movement of the turret brings the cap and body together to the position shown in Fig. 11 where the upstanding portion of the flange on the cap is bent around the flange of the body, due to the groove 129 at the lower end of the socket holding the body. Thus assembly of the parts under the pressure applied by the descending movement of the turret against the part 138 and the spring 134 is accomplished. Of course the part 138 moves down along the post 128 and the rods 130 and cross head 131 move with the part 138. As the turret rises, the assembled capsule with the gas compressed therein is carried to the ejector due to the quarter turn imparted to the turret by the groove 17 and pins 16. At the same time another cap has been fed and another capsule body moved into alignment therewith, so that when the turret descends again, another capsule body and cap will be assembled and the one which has been assembled will be ejected. The capsule bodies are fed onto part 117 during elevation of the turret, and at the same time caps are fed onto post 128. The steps above described are carried out successively and at a fairly rapid rate.

I claim:

1. In apparatus for charging capsules of the character described, including a body and cap, with gas while uniting the cap and body, a carrier for the body, a support for the cap, means to impart relative approaching movement between said carrier and support to effect union of said body and cap, means on said carrier and support forming a chamber housing the cap and body in spaced relation during said approaching movement, and means to supply a charging fluid into said chamber during said approaching movement to be compressed between said body and cap and sealed in the capsule under pressure.

2. Apparatus for assembling and sealing capsules of the character described comprising, a turret provided at predetermined intervals with sockets to receive the bodies of the capsules, a support, means to reciprocate said turret relative to said support, means to rotate said turret, means on said support to successively insert said bodies in said sockets, means operable by movement of said turret toward said support to unite said bodies to the caps of the capsules, and means to successively feed said caps to said uniting means.

3. Apparatus for assembling and sealing capsules of the character described comprising, a turret provided at predetermined intervals with sockets to receive the bodies of the capsules, a support, means to reciprocate said turret relative to said support, means to rotate said turret, means on said support to successively in-

sert said bodies in said sockets, means operable by movement of said turret toward said support to unite said bodies to the caps of the capsules, means to successively feed said caps to said uniting means, and means to lock the turret against rotation during assembling of the caps and bodies.

4. Apparatus for assembling and sealing capsules of the character described comprising, a turret provided at predetermined intervals with 10 sockets to receive the bodies of the capsules, a support, means to reciprocate said turret relative to said support, means operable by reciprocating movement of said turret to rotate said turret, means on said support to successively insert 15 said bodies in said sockets, means operable by movement of said turret toward said support to unite said bodies to the caps of the capsules, and means to successively feed said caps to said uniting means.

5. Apparatus for assembling and sealing capsules of the character described comprising, a turret provided at predetermined intervals with 25 sockets to receive the bodies of the capsules, a support, means to reciprocate said turret relative to said support, means to rotate said turret, means on said support to successively insert 30 said bodies in said sockets, means operable by movement of said turret toward said support to unite said bodies to the caps of the capsules, means to successively feed said caps to said uniting means, and means for removing said assembled capsules from said socket.

6. Apparatus for assembling and sealing capsules of the character described comprising, a 35 turret provided at predetermined intervals with sockets to receive the bodies of the capsules, a support, means to reciprocate said turret relative to said support, means to rotate said turret, means on said support to successively insert 40 said bodies in said sockets, means operable by movement of said turret toward said support to unite 45 said bodies to the caps of the capsules, means to successively feed said caps to said uniting means, and means operable during rotative movement of said turret to remove the assembled capsules from said sockets.

7. Apparatus for assembling, charging, and sealing capsules of the character described, comprising a turret provided at predetermined intervals with sockets to receive the bodies of the capsules, a support, means to reciprocate said turret toward and away from said support, means to rotate said turret distances substantially equal to the spaces between said sockets, means on 50 said support to successively insert said bodies in said sockets, means operable by movement of said turret toward said support to unite said bodies to the caps of the capsules, said means forming in conjunction with said sockets, a 55 chamber in which gas is compressed and forced into the capsules during the assembling of the bodies and caps, and means to successively feed said caps to said uniting means.

8. Apparatus for assembling, charging, and sealing capsules of the character described, comprising a turret provided at predetermined intervals with sockets to receive the bodies of the capsules, a support, means to reciprocate said 70 turret toward and away from said support, means operable by reciprocating movement of said turret to rotate said turret distances substantially equal to the spaces between said sockets, means on said support to successively insert said bodies 75

in said sockets, means operable by movement of said turret toward said support to unite said bodies to the caps of the capsules, said means forming in conjunction with said sockets, a chamber in which the gas is compressed and forced into the capsules during the assembling of the bodies and caps, and means to successively feed said caps to said uniting means.

9. Apparatus for assembling, charging, and sealing capsules of the character described, comprising a turret provided at predetermined intervals with sockets to receive the bodies of the capsules, a support, means to reciprocate said turret toward and away from said support, means operable by reciprocating movement of said turret to rotate said turret distances substantially equal to the spaces between said sockets, means on said support to successively insert said bodies in said sockets, means operable by movement of said turret toward said support to unite said bodies to the caps of the capsules, said means forming in conjunction with said sockets, a chamber in which the gas is compressed and forced into the capsules during the assembling of the bodies and caps, means to successively feed said caps to said uniting means, and means to lock the turret against rotation during assembly of the bodies and caps.

10. Apparatus for assembling, charging, and sealing capsules of the character described, comprising a turret provided at predetermined intervals with sockets to receive the bodies of the capsules, a support, means to reciprocate said turret toward and away from said support, means to rotate said turret distances substantially equal to the spaces between said sockets, means on said support to successively insert said bodies in said sockets, means operable by movement of said turret toward said support to unite said bodies to the caps of the capsules, said means forming in conjunction with said sockets, a chamber in which the gas is compressed and forced into the capsules during the assembling of the bodies and caps, means to successively feed said caps to said uniting means, and means for removing said assembled capsules from said sockets.

11. In apparatus for assembling capsules of the character described each including a body and a cap, a turret provided with a plurality of spaced sockets to receive the bodies of the capsules, a support in spaced relation to the turret, means to rotate the turret step by step distances substantially equal to the spaces between the sockets, a supply magazine for the bodies, a post mounted on the support, means to reciprocate the turret toward and away from the support and post, and means to oscillate the post to receive in one position a body from the magazine when the turret is moved away from the support and to insert said body into one of the sockets as the turret approaches said support.

12. In apparatus for assembling capsules of the character described each including a body and a cap, a turret provided with a plurality of spaced sockets to receive the bodies of the capsules, a support in spaced relation to the turret, means to rotate the turret step by step distances substantially equal to the spaces between the sockets, a supply magazine for the bodies, a post mounted on the support, means to reciprocate the turret toward and away from the support and post, means to oscillate the post to receive in one position a body from the magazine when the turret is moved away from the support

and to insert said body into one of the sockets as the turret approaches said support, means remote from said post and body supply magazine to receive a cap to be united to said body, and means operable by movement of said turret toward said support to unite said body and cap.

13. The structure of claim 12, wherein the socket and the cap receiving means are each provided with die faces and the caps and bodies are provided with flanges disposed over said die faces to be crimped together by the relative approaching movement of said die faces as the turret moves toward said support.

14. In apparatus for assembling capsules of the character described each including a body and cap, a turret having a plurality of spaced sockets, a support, means to reciprocate said turret toward and away from the support, means operable by said reciprocating movements of the turret to impart rotative movement thereto, means operable during descending movement of the turret to insert a capsule body into one of the sockets, means on the support to receive a cap, and means operable during ascending movement of the turret to feed a cap to said cap receiving means, said cap receiving means and sockets having cooperating elements to unite the bodies and caps upon descending movement of the turret.

15. In apparatus for assembling capsules of the character described each including a body and cap, a turret having a plurality of spaced sockets, a support, means to reciprocate said turret toward and away from the support, means operable by said reciprocating movements of the turret to impart rotative movement thereto, means operable during descending movement of the turret to insert a capsule body into one of the sockets, means on the support to receive a cap, and means operable during ascending movement of the turret to feed a cap to said cap receiving means, said cap receiving means and sockets having cooperating elements to unite the bodies and caps upon descending movement of the turret, and means to lock the turret against rotation during assembly of the bodies and caps.

16. In apparatus for assembling capsules of the character described each including a body and cap, a turret having a plurality of spaced sockets, a support, means to reciprocate said turret toward and away from the support, means operable by said reciprocating movements of the turret to impart rotative movement thereto, means operable during descending movement of the turret to insert a capsule body into one of the sockets, means on the support to receive a cap, means operable during ascending movement of the turret to feed a cap to said cap receiving means, said cap receiving means and sockets having cooperating elements to unite the bodies and caps upon descending movement of the turret, and means operable during rotative movement of the turret to remove the assembled body and cap from its socket.

17. In apparatus for charging capsules of the character described, including two parts, namely, a body and a cap, a carrier for one of the parts, a support for the other part, means to impart relative transverse movement between said support and carrier intermittently, means to impart relative approaching movement between said carrier and support to effect union of said body and cap, and means to supply a charging fluid between said body and cap during relative approaching movement thereof.

CARL F. LOZON.
